US00D940417S

(12) **United States Design Patent** (10) **Patent No.:** **US D940,417 S**
(45) **Date of Patent:** **** Jan. 4, 2022**

(54) **VACUUM CLEANER**

(71) Applicant: **SHARKNINJA OPERATING LLC**,
Needham, MA (US)

(72) Inventors: **Scott B. Niedzwecki**, East Walpole,
MA (US); **Owen R. Johnson**,
Needham, MA (US); **Luis A. Canas**,
Stoughton, MA (US)

(73) Assignee: **SHARKNINJA OPERATING LLC**,
Needham, MA (US)

(**) Term: **15 Years**

(21) Appl. No.: **29/663,991**

(22) Filed: **Sep. 20, 2018**

Related U.S. Application Data

(63) Continuation of application No. 29/611,768, filed on
Jul. 25, 2017, now Pat. No. Des. 868,400.

(51) **LOC (13) Cl.** **15-05**

(57) **CLAIM**

The ornamental design for a vacuum cleaner, as shown and described.

DESCRIPTION

FIG. 1 is a perspective view of a vacuum cleaner, showing the new design, with a dust container cover in an open position;

FIG. 2 is a front view thereof;

FIG. 3 is a back view thereof;

FIG. 4 is a left side view thereof;

FIG. 5 is a right side view thereof;

FIG. 6 is an enlarged top view thereof;

FIG. 7 is an enlarged bottom view thereof; and,

FIG. 8 is another perspective view thereof with the dust container cover in a closed position.

The broken lines in the drawings depict portions of the vacuum cleaner that form no part of the claimed design.

1 Claim, 7 Drawing Sheets
